TO THE LITCHFIELD MANUFACTURING COMPANY, OF WATERLOO, IOWA, A CORPO-
RATION OF IOWA.

COMPOSITE METAL WHEEL.

1,297,973.

Specification of Letters Patent. Patented Mar. 18, 1919.

Application filed July 27, 1917. Serial No. 183,054.

To all whom it may concern:

Be it known that we, HENRY L. LITCHFIELD and CLARENCE E. SHIPLET, citizens of the United States, residing at Waterloo, county of Blackhawk, State of Iowa, have invented a certain new and useful Improvement 5 in Composite Metal Wheels, and declare the following to be a full, clear, and exact description of the same, such as will 10 enable others skilled in the art to which it pertains to make and use the same, reference being had to the accompanying drawings, which form a part of this specification.

The present invention has for its object 15 to produce a light, powerful and durable metal wheel. It relates particularly to spoked wheels and, specifically considered, may be said to have for its object to produce a connection between the hub and the spokes 20 which shall have the characteristics of integrality while at the same time permitting the wheel to possess the advantages of having spokes and a hub made of metal differing in characteristics.

25 The various features of novelty whereby the present invention is characterized will hereinafter be pointed out with particularity in the claims; but, for a full understanding of the present invention and of its objects 30 and advantages, reference may be had to the following detailed description taken in connection with the accompanying drawings, wherein:

Figure 1 is a side elevation of a wheel arranged in accordance with a preferred form 35 of the present invention;

Fig. 2 is an edge view of the wheel;

Fig. 3 is a section taken in part on line 40 3—3 of Fig. 1 and in part on a plane somewhat nearer the axis;

Fig. 4 is a central transverse section on an enlarged scale;

Fig. 5 is a section taken approximately on line 5—5 of Fig. 4;

Fig. 6 is a central longitudinal section 45 through the hub end of one of the spokes, on a larger scale than Figs. 4 and 5; and

Fig. 7 is a section taken approximately on line 7—7 of Fig. 6.

50 Referring to the drawings, 1 represents a rim, preferably of rolled steel, to which the outer ends of spokes, 2, also preferably of steel, are attached in any suitable way. The spokes are arranged in two groups the outer

ends of which lie preferably in the same 55 plane, extending at right angles to the axis of the wheel, while the inner or hub ends lie on opposite sides of said plane; and the spokes of the two groups alternating with each other in the circumferential direction. 60

The inner or hub ends of the spokes are cast into a hub, 3, in such a manner that a permanent rigid union between the spokes and the hub, and a strong and comparatively light hub are obtained. This is accomplished by making the hub in the form of a body member having projecting bosses, 4, surrounding the spoke ends; the bosses being connected by diagonal ribs or braces, 5, by means of which each boss is connected to the 70 two nearest bosses in the opposite group.

Each spoke is so fashioned at its inner end that there will be an effective mechanical interlocking between it and the metal of the hub in a direction to prevent separation in 75 the radial direction. Furthermore, the inner end of each spoke is preferably so shaped that there will be a fusion of the metal when the hub is cast in place, resulting in an actual union of the metal of the spokes and 80 hub as distinguished from a mere mechanical joint. It is desirable that the shaping of the inner ends of the spokes to produce the results sought be such as to leave the cross sectional area substantially unimpaired. 85

The above ends are accomplished by flattening out, as indicated at 6, the inner end of each spoke so as to enlarge it transversely in one direction without reducing the cross sectional area. The flattened portion of each 90 spoke is cupped or recessed on opposite sides, as indicated at 7, so as to produce in the center a thin web, 8, through which a hole, 9, may be punched. The extreme inner end of each spoke is preferably left thicker, as indicated at 10, than the thickness of the flattened portion. Just outwardly from each flattened portion each spoke is preferably enlarged or made to bulge somewhat, as indicated at 11, the enlarged portions, 11, registering with the outer ends of the bosses in which the inner ends of the spokes are seated. 100

When the spokes are laid in place in the mold for the hub and molten metal is poured 105 into the mold, this metal not only flows into the recesses and through the opening in each spoke but, because of the thin web-like char-

acter of the portions surrounding the openings in the spokes, fusing of this metal occurs so that there will be a considerable part of the web-like member of each spoke which 5 forms with the metal of the hub a single seamless structure.

It will thus be seen that since the cross sectional area of each spoke is substantially unimpaired at the joint, it is not weakened in 10 any way; because of the mechanical interlocking of the spokes with the hub, displacement without first destroying the hub cannot take place; because of the fusing of portions of the metal of the spokes, a union is effected 15 which will prevent gradual loosening of the joint such as might occur if there were only a mechanical interlock; and because of the enlargements in the spokes where they enter the bosses in the hub, increased strength at 20 points where breakage would be most apt to occur, is secured.

While there is illustrated and described with particularity only a single preferred form of this invention, it is not desired that 25 this invention be limited to the exact structural details thus illustrated and described; but it is intended to cover all forms and arrangements which come within the terms of the present invention constituting the ap- 30 pended claims.

Claims:

1. In a wheel, spokes, and a hub cast about the inner ends of the spokes, the said inner end of each spoke having a part gradually 35 merged into a thin web portion united to the metal of the hub by fusion.
2. In a wheel, spokes, and a hub cast about the inner ends of the spokes, each spoke having at its said inner end a portion terminating 40 in a web sufficiently thin to have become fused by the molten hub metal.
3. In a wheel, spokes, and a hub cast about the inner ends of the spokes, the inner end of each spoke being gradually reduced to a per- 45 forated thin web portion through which the metal of the hub extends and to which it is united by fusion.
4. In a wheel, spokes, and a hub cast about the inner ends of the spokes, each spoke hav-

ing its said inner end gradually reduced to a 50 perforated portion sufficiently thin to have become fused by the molten hub metal passing through the perforated portion.

5. In a wheel, metal spokes having their inner ends flattened and recessed to produce 55 a thin web surrounded by thicker metal, and a hub cast around the flattened and recessed parts of the spokes.

6. In a wheel, metal spokes having their inner ends flattened and recessed to produce 60 a thin web reinforced by adjacent portions of thicker metal, said web being perforated, and a hub cast around the flattened and recessed parts of the spokes, the metal of the hub ex- 65 tending through the web and fused to those portions of the web surrounding the latter portions of the hub metal.

7. In a wheel, spokes having their inner ends flattened, the flattened ends being pro- 70 vided with opposed depressions in the two flat faces thereof to produce a thin central web portion, each thin web portion being perforated, and a hub cast around and through the flattened inner ends of the spokes.

8. In a wheel, spokes having their inner 75 ends flattened, the flattened ends being pro- vided with opposed depressions in the two flat faces thereof to produce a thin central web portion, each thin web portion having a 80 large opening extending through the same, and a hub cast around and through the flattened inner ends of the spokes and fused to those parts of the webs surrounding the openings therein.

9. In a wheel, spokes each of which is flat- 85 tened in proximity to its inner end to produce a thin web portion and adjacent portions of thicker metal having a combined cross-sectional area equal to that of the spoke, each web being perforated, a hub cast about 90 and through the inner ends of the spokes and the flattened portions thereof, and each spoke having an enlargement or bulge at the point where it meets the hub.

In testimony whereof we sign this speci- 95 fication.

HENRY L. LITCHFIELD.
CLARENCE E. SHIPLEY.
